UNITED STATES PATENT OFFICE.

AUGUST F. BLESCH AND JONAS HERRMANN, OF COLUMBUS, OHIO.

DESIGN FOR A FLUSHING-TANK.

SPECIFICATION forming part of Design No. 19,850, dated May 27, 1890.

Application filed April 18, 1890. Serial No. 348,555. Term of patent 14 years.

To all whom it may concern:

Be it known that we, AUGUST F. BLESCH and JONAS HERRMANN, citizens of the United States of America, residing at Columbus, in the county of Franklin and State of Ohio, have invented and produced a new and original Design for a Flushing-Tank for Water-Closets and Urinals, of which the following is a specification, reference being had therein to the accompanying drawings.

Figure 1 of the drawings is a front perspective view of the tank, showing our design. Fig. 2 is a rear perspective view of the same.

The leading feature of our design is the ornamentation of the entire front and end outer surfaces, which represents molding, the projecting portions of which, when viewed from below, appear to overhang each other from the top downward. The back of the tank is vertical, while the front and ends slope outward in the direction of the top, where the tank is of considerably greater area than at the bottom.

Referring to the drawings, A is the bottom of the tank, which is rectangular.

B is the back, which is plain and stands vertical; but it is narrower at the bottom than

at the top C, it gradually increasing in width from its lower edge to its upper edge, as seen in Fig. 2.

D represents the ends, whose outer surfaces are ornamented throughout to represent molding having alternate receding portions 1 and projecting portions 2.

E is the front of the tank, whose outer surface is likewise ornamented throughout to represent molding, which corresponds to that on the sides.

As will be seen in Fig. 1, the front and ends slope gradually outward from the bottom up, the projecting portions of the surface ornamentation being in different planes.

What we claim is—

The design for a flushing-tank for water-closets and urinals, herein shown and described.

In testimony whereof we affix our signatures in presence of two witnesses.

AUGUST F. BLESCH.
JONAS HERRMANN.
